US00D943421S

(12) **United States Design Patent** (10) Patent No.: **US D943,421 S**
(45) Date of Patent: **** Feb. 15, 2022**

(54) **DISPENSING DEVICE**

- (71) Applicant: **Silgan Dispensing Systems Corporation**, Grandview, MO (US)
- (72) Inventor: **Brandon Ramsuer**, Henrico, VA (US)
- (73) Assignee: **SILGAN DISPENSING SYSTEMS CORPORATION**, Grandview, MO (US)
- (**) Term: **15 Years**
- (21) Appl. No.: **29/707,601**
- (22) Filed: **Sep. 30, 2019**

Primary Examiner — Catherine A Tuttle*(74) Attorney, Agent, or Firm* — Barlow, Josephs & Holmes, Ltd.; Stephen J. Holmes**(57) CLAIM**

The ornamental design for a dispensing device, as shown and described.

DESCRIPTION

FIG. 1 is a perspective view of a dispensing device embodying my new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken lines depict elements of the dispensing device that form no part of the claimed design.
